UNITED STATES PATENT OFFICE.

HENRY PRICE BALL, OF NEW YORK, N. Y., ASSIGNOR TO GENERAL INCANDESCENT ARC LIGHT COMPANY, OF NEW YORK, A CORPORATION.

HIGH-TENSION OIL-SWITCH.

No. 839,703.

Specification of Letters Patent.

Patented Dec. 25, 1906.

Application filed July 2, 1902. Serial No. 114,093.

To all whom it may concern:

Be it known that I, HENRY PRICE BALL, a citizen of the United States, residing at New York city, county and State of New York, have invented certain new and useful Improvements in High-Tension Oil-Switches, of which the following is a specification.

My invention relates to oil-switches of the type especially designed for use with circuits transmitting high-tension large quantity currents.

My invention consists in the mechanism for electrically actuating the switch from a distance, and, further, in the means employed for automatically changing the circuit connections through the actuating mechanism.

The object of my invention is to provide mechanism for actuating the switch from a distance and for maintaining the direction of movement given to the switch until it has completed the required movement in opening or closing the switch and irrespective of the condition or position of the primary switch or device located at a distance through the instrumentality of which the switch mechanism is first energized.

The accompanying drawings will serve to illustrate my invention and in which similar letters and numerals indicate like parts.

Figures 1, 2, and 3 are diagrams illustrating the circuit connections between the mechanism for actuating the oil-switch, the source of power, and the primary energizing device at a distance and also showing the successive positions of the parts. Fig. 4 is a vertical section through a vault containing an oil-switch with its actuating mechanism shown as a side elevation. Fig. 5 is an enlarged side elevation of the upper portion of the switch-actuating mechanism. Fig. 6 is an enlarged front elevation of the upper portion of the switch-actuating mechanism. Fig. 7 is a corresponding view with the cam in section and illustrates the position of the lever which controls the switch-lever just before the switch-lever is thrown to the left. Fig. 8 is a top view. Fig. 9 is a rear elevation of the switch mechanism which is located above the oil-wells.

Referring to the drawings, Figs. 1, 2, and 3 illustrate diagrammatically the general relation existing between the main distributing system, the oil-switch, and its actuating and energizing mechanism. In these figures, A indicates the three conductors of an alternat-

ing distributing-current system; B, oil-wells; C, bridging devices coacting with the oil-wells; D, source of constant current; E, hand-switch located at a distance from the oil-wells; F, lever of hand-switch; G G', solenoids located at the oil-wells for raising and lowering the bridging devices and for moving the switch-lever H, and I I' I² J J' J² contacts coöperating with the switch-lever H and hand-switch E, through the instrumentality of which the solenoids G G' may be thrown in circuit with the dynamo D.

In Fig. 1 of the diagram the parts are shown in the position which they would occupy with the bridging devices elevated and the circuits through the oil-wells broken. It will be observed in this figure that the knife-blade F of the hand-switch E occupies a midway position and that the switch-lever H covers the contacts I I' of the actuating mechanism located at the left.

In Fig. 2 the knife-blade F of the hand-switch is shown as thrown to the left and the switch-lever H covers the contacts I I² at the left and that the bridging devices are half-way in the oil-wells.

In Fig. 3 the knife-blade F of the hand-switch is shown as thrown to the right, and the switch-lever H covers the contacts J J'. If this figure was extended, it would show the bridging devices as fully inserted within the oil-wells and in electrical contact with the contact devices contained within the oil-wells.

The operation of the device so far as relates to the action of the energizing device at a distance through the hand-switch upon the actuating mechanism and the actuating mechanism upon the energizing device so far as the circuit connections are concerned is as follows:

Assuming the knife-blade F of the hand-switch E to be thrown to the left—i. e., into the position shown by the dotted lines, Fig. 1—a current will flow from dynamo D through knife-blade F, conductor K, by switch-lever H, this lever bridging the contacts I I', solenoid G, and conductor L, back to dynamo. The pull of the solenoid G acting through its core will shift the switch-lever H to the left to cover contacts I² I, or otherwise into the position shown in Fig. 2. It will be observed that when the switch-lever H covers the contacts I² I or J² J that the solenoid G or G' is

in circuit with the dynamo and is independent of the hand-switch. The object of this arrangement is to provide that the current from the dynamo D will be transmitted through the solenoid at the time energized until the limit of movement of its core is reached and irrespective of the position of the hand-switch.

The movement of the switch mechanism as described serves to close the circuits through the oil-wells. When the limit of movement of the core of the solenoid G has been reached, the switch-lever H is automatically shifted to the right through the action of the spring mechanism, to be hereafter described, to cover the contacts J J'. When it is desired to open the switch, the knife-blade F of the hand-switch E is turned to the right—i. e., to the position shown in Fig. 3. With the knife-blade F in this position the current from the dynamo will be transmitted through the solenoid G', which, attracting its core, will move the switch-lever H to the right to cover the contacts J J'. At this point after the movement of the core of solenoid G' the switch-lever will be automatically shifted to again cover the contacts I I'. Thus it will be seen that by throwing the hand-switch E in one direction the oil-switch will be thrown from its open position (shown in Fig. 1) through the intermediate position in Fig. 2 to its closed position, (shown in Fig. 3,) and upon moving the hand-switch in the opposite direction the reverse movement of the oil-switch will take place.

The construction of the oil-switch illustrated in Fig. 4 has been described by me in a prior application, Serial No. 95,609, filed February 25, 1902. I shall therefore in this specification give only such a description of the oil-switch as is necessary to make the succeeding description of the switch-actuating mechanism intelligible.

M indicates a vault or receptacle in which the oil-wells are located; N, oil-wells; O, movable platform upon which the oil-wells are mounted; P, non-conducting rod, connected at the lower end to the bridging devices Q of the oil-wells and at the upper end to the switch-actuating mechanism.

The mechanism for actuating the switch is mounted upon the top of the vault or receptacle and consists of a suitable standard R, in the upper end of which and arranged to rotate in suitable bearings is a shaft S. Secured to the rear end of this shaft is a lever T, the lower end of which is provided with the horizontally and rearwardly projecting arms T' and the cam-head T''. Loosely pivoted upon the shaft S is an arm U, the lower end of which is situated between the projecting arms T' of the lever T. The distance between these arms is somewhat greater than the width of the arm U, so that when the le-

ver T is rotated in either direction it may be moved a short distance before engaging with the arm U. The outer end of the arm U is connected through a rod V with the cross-head W, connected to the non-conducting rod P, which carries the bridging devices Q. Connected to the opposite side of the cross-head from the rod V is a sleeve 10, arranged to move vertically upon the vertical rod 11. This rod 11 is connected at one end to the top of the receptacle M and at the other end to the standard R.

Secured to the front end of the shaft S is an arm 12, carrying a projecting pin 13. Interposed between this pin and the base of the standard R is a helical spring 14. The function of this spring is to balance the weight of the lever T and arm U, the non-conducting rod P, and bridge Q. Mounted on the same end of the shaft is a band-wheel 15, over which is placed a flexible band 15^a somewhat narrower than the band-wheel, connected at its opposite ends to the cores 16 16^a of the solenoids G G'. The band is secured to the band-wheel by means of a screw 17, Fig. 6. The band-wheel has formed in its periphery a concave opening 18, the purpose of which will hereinafter be described. Mounted also upon and secured to the same end of the shaft S and back of the band-wheel is a cam-wheel 19, Fig. 6, having formed in its rear surface a cam-slot 20.

Secured to the standard R is a plate of insulating material 21, upon the upper face of which are located the contacts I I' I² J J' J². These are preferably constructed in the manner shown in Fig. 8—i. e., as pairs of oppositely-disposed spring-plates having contact-surfaces. Secured to the front of the plate 21 is a bracket 22, having a horizontally laterally projecting arm 23, which supports a rearwardly-projecting fixed shaft 24. Pivotedly mounted upon this shaft is a switch-lever H, formed of a lever 25 and a contact-blade 26, which engages the contacts I I' I² J J' J². Projecting horizontally and forwardly from the lower end of the lever 25 is a pin 27, on which is a roller 28. This roller 28 is adapted to take in the cam-slot 20 of the cam 19.

Also pivotedly mounted upon the shaft 24 is a short lever 29, carrying at its lower end the roller 30, which bears normally upon the periphery of the band-wheel 15. The upper end of this lever is provided with an arm 31, from which projects backwardly and horizontally a pin 32. A similar pin 33 projects forwardly and horizontally from the lever 25.

Surrounding the shaft 24 is a coiled spring 34, the ends of which are crossed and bear, in Fig. 6, the end 35 over the pin 33 on the lever 25 and the end 36 under the pin 32 on the lever 29. In Fig. 7 the pin 32 is shown as bearing on the end 35 of the spring 34 and the end 36 upon the pin 33.

37, Figs. 6 and 8, represents elastic stops in the path of movement of the lever T. Projecting forwardly and horizontally from the arm U is a pin 38, which pin is adapted 5 to coact with the ends of the blocks 39 40. These blocks are pivoted at 41 41^a. Arranged over the block 39 is a spring 42 and a corresponding spring 43 under the block 40. Projecting horizontally and forwardly on the 10 blocks 39 40 and rigidly mounted thereon are the pins 44 44^a. These blocks serve to lock the lever U in either the opened or closed position of the switch.

The operation of the switch mechanism 15 will be readily understood.

When the hand-switch F is shifted, as has heretofore been described, to one position or the other, the solenoid G or G' is thrown into circuit with the dynamo D. One of the solenoids at such time will attract its core, and, assuming it to be the solenoid G', its core 16^a will be pulled down and through the action of the band 15^a on the band-wheel 15 the shaft S will be rotated to the right. The rotation of the shaft S to the right will move the lever T in the arc of a circle to the left. When the movement of the lever T commences, its cam-head T² will move over the pin 44, projecting from the block 40 and 20 press the block out of the path of movement of the lever, which will move from the position shown in the dotted lines, Fig. 6, to a position one hundred and eighty degrees distant and will move with it the arm U from 25 the position shown in Fig. 3 to the position shown in Fig. 1, thereby making traction upon the rods V P and lifting the bridging device Q out of the oil-wells. The rotation of the shaft S will also impart a corresponding movement in the same direction to the cam-wheel 19.

As the cam-wheel 19 rotates to the right the lower surface of the cam-slot 20 moves under the roller 28 on the lever 25 of the 45 switch-lever H. It will be observed that by reason of the shape of the cam-slot the roller 28 is first slightly raised, then lowered as the roller approaches the circular portion of the cam-slot. The effect of this movement is 50 to move the contact-blade 26 of the switch-lever H to the right from the position where it covers the contacts J J' to that where it covers the contacts J J². As further rotation of the cam-wheel 19 to the right takes 55 place the roller 28 moves through the circular portion of the cam-slot, and as the circular portion is concentric with the axis of rotation of the cam-wheel no movement is given to the switch-lever H. While the 60 switch-lever H is thus being moved in response to the action of the cam-slot upon the roller 28 the roller 30 on the lower end of the lever 29 is passing over the periphery of the band-wheel 15. When this roller 30 reaches 65 the opening 18 on the band-wheel, it is forced

into said opening by the spring 34 acting upon the pins 32 33. As soon as the roller 30 drops into the opening 18 it is not free to escape until the band-wheel has rotated the lever 29 about the shaft 24, carrying the 70 lower end of the lever to the right. The effect of this movement is to reverse the position of the pins 32 33 relative to the ends 35 36 of the spring 34, thus changing them from the position shown in Fig. 6 to that 75 shown in Fig. 7. Obviously if the ends of the levers 25 and 29 were free the ends 35 36 of the springs 34 would move toward each other until both of said pins were engaged by both ends of the spring—that is, until both 80 pins lay in a radial line extending from the center of the shaft 24. When the ends of the spring are spread apart, they tend to draw the ends of the levers 25 and 29 together. When the parts are in the position shown in 85 Fig. 6, this tendency has the effect of causing the lower ends of the levers to move toward the shaft S, while when the opening 18 of the band-wheel has caused the lower end of the lever 29 to be thrown to the right of the lower 90 end of the lever 25 this tendency has the effect of causing the lower end of the lever 25 to move away from said shaft S. Consequently as soon as the cam has moved far enough to bring the radial portion of the 95 cam-slot in line with the roller 28 the roller flies outward, thereby throwing the switch-lever H to the left, so that the contact-blade 26 engages the contacts I I'. This opens the operating-solenoid circuit and the parts stop 100 in the position shown in Fig. 1, with the oil-switch open. In this position of rest the roller 28 does not pass beyond the cam-slot, but bears against a circumferential shoulder in said slot, which prevents its further outward movement, and thereby retains the contact-blade 26 in engagement with the contacts I I' and prevents its movement to the contacts I I².

It will be observed that when the contact-blade 26 of the switch-lever H is thrown on the one hand from the contacts J J' to J J² or on the other from the contacts I I' to I I² the hand-switch E is cut out of circuit. By reason of this arrangement the initial movement given the oil-switch in either direction through the solenoids G G' will be continued until the end of the stroke of the cores 16 16^a, as the case may be, and cannot be interfered with by manipulating the hand-switch E.

When the hand-switch E is thrown so as to effect a reverse movement of the switch by energizing the solenoid G, the roller 28 soon passes beyond the circumferential shoulder of the cam-slot into engagement 115 with the periphery of the cam-wheel, and in so doing throws the contact-blade 26 of the switch-lever H to the contacts I I², thus rendering the solenoid-circuit independent of further manipulations of the hand-switch 120 130

E, as previously pointed out. During the further return movement of the parts the contact-blade 26 of the switch-lever H is maintained in engagement with the contacts I I' by the continued engagement of the roller 28 with the periphery of the cam-wheel 19. This is continued until the roller 28 passes into the radial portion of the cam-slot into the position shown in Fig. 3, thereby throwing the contact-blade 26 of the switch-lever H to the contacts J J'. This breaks the circuit of the actuating-solenoid G and leaves the circuits in a position to be completed for the reverse movement of the oil-switch upon the proper throwing of the hand-switch E. During this return movement the roller 30 on the lever 29 again engages the opening 18 in the band-wheel and the pins 32 and 33 interchange positions relative to the ends of the spring 34, as previously pointed out. This occurs before the roller 28 reaches the radial portion of the cam-slot, and thus the spring 34 exerts a tendency to draw the roller 28 into said portion of the slot as soon as it is reached. This leaves the parts in the position shown in Figs. 6 and 3, with the oil-switch closed and the circuits in readiness to repeat the operation to open the oil-switch upon throwing the blade F of the hand-switch E to the position shown in Fig. 3, which represents the parts in the position assumed by them just before the oil-switch begins to open.

It will be observed that under the action of the spring device the circuit connections through the switch are automatically altered. I wish it understood that I do not limit myself to the precise mechanism described for automatically changing the circuit connections.

Having thus described my invention, I claim—

1. In an electric switch, the combination of a shaft, a band-wheel on said shaft, a band over said band-wheel, a pivoted switch-lever, a series of contacts, spring mechanism coacting with said switch-lever to automatically shift it from one contact to another, a bridging member, and mechanism introduced between the shaft and the bridging member.

2. In an electric switch, the combination of a shaft, a band-wheel on said shaft, having a cam-slot therein, a pivoted switch-lever provided with a pin which co-operates with said cam-slot, a series of contacts arranged in the path of movement of the switch-lever, and means energized by the rotation of said shaft and adapted to coact with said lever to shift it from one contact to another.

3. In an electric switch, and in combination with the actuating mechanism of the switch, a band-wheel provided with a recess, a cam-wheel having a cam-slot therein, a lever carrying at one end a bridging device and at the other end a wheel adapted to move in

said cam-slot, a second lever adapted to co-operate with said band-wheel, and a tension device interposed between said levers.

4. In an electric switch, and in combination with the actuating mechanism of the switch, a band-wheel provided with a recess, a cam-wheel having a cam-slot therein, a lever carrying at one end a bridging device and at the other end a wheel adapted to move in said cam-slot, contacts with which said bridging device coacts, a second lever adapted to co-operate with said band-wheel, and a tension device interposed between said levers.

5. In an electric switch and in combination with the actuating mechanism, means for cutting the actuating mechanism into and out of circuit with the source of electric energy after the primary movement of the actuating mechanism has begun, said means consisting of a band-wheel having a cavity therein, a cam-wheel having a cam-slot, a lever coacting with said band-wheel, a lever coacting with said cam-slot, a bridging device, spring-contacts coacting with said bridging device, and means interposed between said levers for causing said bridging device to make a quick break from the contacts with which it coacts.

6. In an electric switch, the combination of a bridging member, actuating means for moving the bridging member, means for overcoming the weight of the bridging member, means for cushioning the movement of the bridging member at the limit of its stroke in either direction, means for locking the bridging member in its open or closed position, contacts connected to different circuits through the actuating means, and a switch-lever moved from one contact to another for changing the circuit connections through the actuating means for moving the bridging member when the limit of movement of the bridging member in either direction has been reached.

7. In an electric switch, the combination of a bridging member, actuating means for moving the bridging member, means for locking the bridging member at the limit of its stroke, means for unlocking the bridging member and imparting a hammer-blow to its moving mechanism, contacts connected in different circuits through the actuating means, a switch-lever shifted from one contact to another for changing the circuit connections through the actuating means for moving the bridging member when the limit of movement of the bridging member in either direction has been reached.

8. In an electric switch, the combination with an oscillatory member, of a pair of actuating-solenoids, a plurality of circuits through each solenoid, a switch for controlling the solenoid-circuits located adjacent said member, and means actuated by said member for throwing said switch to different operative

positions to close different circuits through each solenoid during the oscillations of said member.

9. In an electric switch, the combination with an oscillatory member, of a pair of actuating-solenoids therefor, a plurality of circuits through each solenoid, a switch-blade pivoted adjacent to said member, coöperating contacts on opposite sides of the central position, the contacts on each side included in the circuits of the respective solenoids, and means actuated by said member for throwing said switch-blade in one direction to different operative positions to close different circuits through each solenoid and to different operative positions to close different circuits through the other solenoid upon the return movement of said member.

10. In an electric switch, the combination with fixed contacts, of a pivoted coöperating switch-blade, an oscillatory member provided with a cam for actuating said blade, a spring for exerting pressure on said blade to maintain it in operative relation to said cam, and means for changing the direction of application of said spring-pressure at definite points in the movement of said oscillatory member.

11. In an electric switch, the combination with a pair of actuating-solenoids, a main circuit and a branch circuit through each of said solenoids, and a hand-switch for closing the

main circuit through either of said solenoids, switching means operated by the energization of one of said solenoids to close the branch circuit through the same solenoid and subsequently break both circuits through said solenoid and leave the main circuit of the other solenoid in condition to be closed by said hand-switch.

12. In an electric switch, the combination with an oscillatory member, a pair of solenoids for controlling the oscillation of said member, a main circuit and a branch circuit through each of said solenoids, of a hand-switch for closing said main circuit through either of said solenoids, and a double-throw switch for further controlling said main circuit and said branch circuit through each of said solenoids, actuated by the movement of the oscillating member in one direction when one of said solenoids is energized to close the branch circuit through the same solenoid and subsequently break both circuits through said solenoid and leave the main circuit of the other solenoid in condition to be closed by said hand-switch.

In testimony whereof I affix my signature in the presence of two witnesses.

HENRY PRICE BALL.
